UNITED STATES PATENT OFFICE.

JOSEPH PERLMUTTER, OF JERSEY CITY, NEW JERSEY.

CUE-TIP HOLDER.

1,270,864.

Specification of Letters Patent.

Patented July 2, 1918.

Application filed September 1, 1917. Serial No. 189,264.

To all whom it may concern:

Be it known that I, JOSEPH PERLMUTTER, a citizen of the United States, residing at Jersey City, in the county of Hudson, State of New Jersey, have invented a new and useful Improvement in Cue-Tip Holders, of which the following description, in connection with the accompanying drawings, is a specification, like characters in the drawings 10 representing like parts.

This invention relates to an improvement in cue tip holders and has for its object to provide a simple device, by means of which a cue tip may be readily and quickly attached to or detached from the end of a billiard cue.

By the method commonly pursued heretofore, when a worn or damaged tip is removed, the end of the cue has to be scraped 20 or sand-papered and nicely trued to properly seat the new tip which is then attached by means of glue or cement, for which reason the cue is rendered useless for varying periods, to allow the glue or cement to harden, but with the use of the socket device, 25 illustrated herein, which is adapted to retain a specially made cue tip, such as is shown and claimed in my application No. 189,263 for patent on an improvement in cue tips 30 filed concurrently herewith, one end of which is inserted in the hitting end of a billiard cue, screw fashion, a tip may be attached in a minute's time, or a worn or damaged tip may be as quickly replaced, the 35 device being readily operated by the fingers without the use of tools.

Other objects will in part be obvious and in part pointed out hereinafter.

In the accompanying drawings:

40 Figure 1 is a side elevational view of the device, of the cue tip and a portion of a billiard cue, with a longitudinal section of the hitting end thereof cut away to show the detail of the screw end of the tip holder.

45 Fig. 2 is a vertical sectional view of the two main portions of the device, and an elevational view of the dowel pins and a cue tip.

50 Fig. 3 is an elevational perspective view of one of the two main portions of the device, showing the dowel pins, by means of which the two portions of the device are held in register with one another, the flanged and socketed head formation and the elongated 55 screw formed end.

In the drawings, the numerals 1 and 2 in-

dicate the head portions of the two main members of the device, identical in shape, form and size, each describing a one-half longitudinal section of a cylinder, 12 indicates the narrowed, elongated and threaded end portions, the combination of which describe a uniform screw, when placed together in register, to be inserted in the small end of a billiard cue.

The ends of the screw portions 12 are tapered and rounded at 11 to facilitate insertion.

The head portion of one main member is provided with a peg or dowel pin 3 and a 70 similar dowel pin 4 is provided in the screw portion adapted for register with and insertion in the walls or borings 5 and 6 of the other main member 1, whereby both main members, when in place, are brought 75 into exact register with each other.

Now regarding the two main members as attached in register with each other, forming a unit, the head portions are recessed at the upper end, the opening describing an internal annular flange 8, the under surface of which 9 is parallel with the bottom of the opening 14 and the end 10, making a positive clutch formation, as applied to the device.

It will be noticed that the base of the head portion describes an annular recess 7 for better seating, securing and preventing the spreading of the open end of the billiard cue 14.

From the above description it will be 90 readily seen that having inserted the base of a cue tip 15 in the recessed head 14 of one of the main portions or halves of the device as Fig. 3, and placed the remaining half of the device in register and juxtaposition 95 therewith, and having inserted both members as a unit, screw fashion, in the end of the cue, until the base 7 engages the end of the cue, as in Fig. 1, both members of the device are thereby held securely in place, the 100 cue tip, the cue tip holder, and the cue forming integrally a single unit.

Having thus described my said improvement, I claim as my invention and desire to secure by Letters Patent under this specification:

1. A cue tip holder, comprising two semi-cylindrical separable members, integrally describing a cylinder, having a recess, with an internal annular flange at the opening thereof, in one end, and a circular recess for seating the end of the cue in the other 110

end, and screw means for attaching to billiard cues and the like.

2. A cue tip holder, comprising two semi-cylindrical members, dowel means for removably maintaining the members in register, a recess at one end with inwardly inclined flange means at the opening thereto, for retaining a cue tip, and at the other end, a circular channel or groove for seating the end of a cue, and screw means for attaching the members to a cue or the like.

3. A cue tip holder, comprising two semi-cylindrical members, dowel means for removably maintaining the members in juxtaposition, cylindrically, a recess at one end with inwardly inclined flange means, at the opening thereto, and in the other end a circular channel or groove, for seating and gripping the cue end, and screw means for attaching the device to a billiard cue or the like.

4. The combination in a cue tip holder, of two semi-cylindrical members, integrally describing a cylinder, having in one end thereof a cylindrical recess, contracted as a flange at the opening thereto, and the opposite end having at the center thereof screw means, integral with the main member, adapted for attaching the device to a billiard cue, and a circular channel or recess interposed between the outer edge and the screw means, for retaining and gripping the end of a billiard cue. 25 30

In testimony whereof I have signed my name to this specification in the presence of two subscribing witnesses.

JOSEPH PERLMUTTER.
